UNITED STATES PATENT OFFICE.

WILLIAM E. GIBBS, OF FANWOOD, NEW JERSEY.

ACETYLENE-GAS GENERATOR.

SPECIFICATION forming part of Letters Patent No. 621,065, dated March 14, 1899.

Application filed November 10, 1898. Serial No. 696,002. (No model.)

To all whom it may concern:

Be it known that I, WILLIAM E. GIBBS, a citizen of the United States, residing at Fanwood, in the county of Union and State of New Jersey, have invented certain new and useful Improvements in Acetylene-Gas Generators, of which the following is a specification.

This invention relates to improvements in acetylene-gas generators, and has especial reference to the type of machine wherein a limited quantity of carbid is dumped down through a chute from time to time into a large quantity of water, the times at which the carbid is thus supplied being automatically determined by the movements of the gas-holder connected to or comprised in the generator. In such machines the water of the generating-tank extends into the chute to form a water seal, and it is found that when the carbid is dumped into the chute more or less gas is generated while the carbid is descending in the chute itself, such gas escaping through the mouth of the chute. When, as is generally the case, there is a considerable proportion of small lumps and fine carbid particles or dust in the charge, this evolution of gas in the chute is very considerable and becomes a matter of serious importance, partly from the waste it incurs, but to a greater extent from the bad odor and the danger resulting therefrom. It has been proposed to obviate this difficulty by the use of a layer of oil in the chute in connection with a deflector or back vent, whereby the gas generated when the carbid strikes the water in the lower portion of the chute is deflected to the upper part of the generating-tank. Such constructions are, however, open to the objection that when the generating-tank is emptied or "drawn off" for the purpose of cleaning same this oil must be drawn off also and then the oil-supply renewed again. Moreover, the layer of oil on top of the water in the chute is apt to be churned up by the violent evolution of gas, so as to mix more or less with the water and to be carried over into the main tank. All such difficulties I overcome by the expedient of having the oil seal out of contact with the water in the main tank. For this purpose I provide at the bottom of the chute a trap containing oil or other inert liquid, the end of

said trap away from the chute being above the water in the main tank, so that the oil of the seal is not in contact with said water. 55 The carbid when dumped down the chute falls into this trap and a conveyer is provided for conveying it through the trap, lifting it out of same, and ejecting it into the main tank. The motion of the conveyer is preferably 60 slow enough to enable the oil to drain away from the carbid before it is ejected into the water, so that very little oil is carried with it. The trap above described is not affected at all by the opening of the generator-tank 65 to clean same and always maintains a sealed closure of the tank when the machine is in use.

In the accompanying drawings, which form a part of this specification, Figure 1 is a vertical section of a generator involving my invention. Fig. 2 is a detail view of the trap. Fig. 3 is a horizontal section of same on line 3 3 of Fig. 1. Fig. 4 is a sectional view of a modified form.

In Figs. 1 and 2, A represents the water-tank of the generator, a the top plate of same, having an opening a', and B a cover having a rim b at its lower edge resting in the water-seal space formed between the top rim of tank A. A chute C extends through the top 75 of cover B and at its lower end extends down into a tank D, forming a trap, this tank D being wholly or partly filled with oil or other liquid which is inert—that is to say, is without action on the carbid. 80

Suitable means, forming no part of my present invention, are provided for feeding the carbid into the chute C. Such means may consist of a series of buckets or cans F, supported in any suitable manner so as to move 85 over the top of the chute. These buckets have hinged bottoms f, with catches f', which are tripped at the moment they pass over the chute to allow the bottom to fall and the carbid to drop into the chute. For causing these cans to be moved *seriatim* over the chute I may arrange a ratchet-lever G, engaging by a pawl g with teeth h in the support H of cans F. This lever may be actuated by engagement with the bell I of the gas-holder J, 90 which is connected by pipe K with the generator-tank A, as shown in Fig. 1. 100

M represents a receptacle which is ordinarily supported in a position directly under

the chute C, so that when the carbid is dumped down the chute it falls into this receptacle. As shown in Figs. 2 and 3, the tank D has an extension at one side, (indicated at D'), and in this extension is arranged the mechanism for moving the receptacle M to carry the carbid through and out of the trap. Such mechanism consists of a lever P, pivoted at p and carrying the receptacle M on one of its arms, the receptacle being adapted to slide radially on said arm, but to move with same in its circumferential motion. On the other arm of the lever P is pivoted, at s, an auxiliary lever S, one end of which engages 15 by a pin-and-slot connection t with a rod T, attached to the door V on one side of receptacle M. Said door is hinged at the bottom and is normally held closed by a catch v. A rod W, sliding vertically in a guiding-seat in the side 20 of pocket or tank extension D', has pivotally attached thereto a link w, which engages with one end of lever S to turn it on its pivot s as the rod W descends. Such descent of the rod is effected by the downward movement of the 25 bell I, which carries a projection j, which after the carbid-can-dumping device has been operated to dump the carbid down the chute strikes a lever X, to which the rod W is pivoted, and forces said rod down. The first effect 30 of this is to cause the lever s to turn on its pivot S, and thus by means of rod T to draw the receptacle inward radially and away from under the chute C. The receptacle then strikes a stop m', which arrests its radial 35 movement, so that the further downward movement of rod W results in the turning of the lever P on its pivot p, thus causing the receptacle to be carried upward and out of the oil in the trap. This motion being comparatively slow, the oil has time to drip out through 40 the loose joints of the door of the receptacle. Finally the receptacle comes to a position over the aperture a in the tank-top, and its catch v strikes a pin v', which disengages it 45 from the door and allows the latter to fall, thus dropping the carbid through the aperture a into the water in the main tank A. The gas-holder will then begin to rise, and the lever being released from projection j is tipped 50 back by a counterweight Y thereon, so as to raise the rod W. This allows the receptacle M to fall back into the trap, the lever P turning on its pivot p. This upward movement 55 of rod W also allows the door V to be pressed to its closed position by a counterweight s', which is attached to that arm of lever S which is connected to the said door. Finally, when the receptacle is all the way down and the door is closed, the rod W, through lever D 60 and rod T, forces the receptacle radially outward on arm P to a position directly under the chute, as before.

While I have above described a special means of carrying out my invention in what 65 I consider the most approved manner, it is clear that other means could be used to convey the carbid through the oil seal. Thus,

as shown in Fig. 4, a simple conveying chain or apron P', with buckets M', could be used to move the carbid, which falls through the chute C directly into said conveyer chain or apron P' and is carried upward by the buckets in the motion of the chain. Such motion may be imparted to the chain by suitable connection to the gas-holder—for example, by 70 projections i' i' on the bell I of such holder striking the ratchet-arm N, engaging by pawl n with a ratchet-wheel Z on one of the shafts z z, on which the conveyer-chain is mounted.

In each of the above forms of my invention 80 the carbid is lifted by the conveyer above the surface of the oil in the trap, and drainage communication is provided for the receptacle or conveyer to the trap, so that the oil may drop back into the trap and not be carried over into the generating-tank. This is 85 essential, as the presence of oil in the generating-tank is not desirable.

Having thus described my invention, what I claim as new therein, and desire to secure 90 by Letters Patent, is—

1. In an acetylene-gas generator, the combination with the water-tank of the generator, of a chute, a trap located at the bottom of the chute, and above the surface of the water 95 in the generating-tank, and containing an inert liquid which extends into the chute but is not in contact with the water in the generating-tank, and a conveyer for conveying the carbid through said liquid, said conveyer 100 having drainage communication with the trap.

2. In an acetylene-gas machine, the combination with the generating-tank containing water, of a chute, a trap located at the bottom of the chute and containing an inert liquid out of contact with the water in the generating-tank, a receptacle having drainage communication with the trap and a device for moving said receptacle from beneath 110 said chute, and upwardly out of said trap, and causing it to eject its contents into the generating-tank.

3. In an acetylene-gas generator, the combination with the generating-tank containing water, of a chute, a trap located at the bottom of the chute and communicating with the interior of the generating-tank at a point above the water-level therein, said trap containing an inert liquid out of contact with the water 115 in the generating-tank of a conveyer located in said trap for conveying the carbid through the same and having drainage communication with the trap, a gas-holder connected with the generating-tank and means controlled by the movement of the gas-holder to operate the said conveyer.

4. In an acetylene-gas generator, the combination with the generating-tank containing water, of a chute, a trap located at the bottom of said chute, a receptacle, a lever carrying the said receptacle, an auxiliary lever connected to said receptacle for shifting it radially on the aforesaid arm, means for limit-

ing such radial movement, and an actuating device acting on the auxiliary lever to cause first a radial and then a rotary movement of the receptacle, whereby the latter is moved 5 from under the chute and is then lifted out of the trap.

5. In an acetylene-gas machine, the combination with the generating-tank containing water, of a chute, a trap located at the bottom of the chute and containing an inert liquid out of contact with the water in the generating-tank, a receptacle having drainage communication with the trap, and a device comprising a pivoted arm supporting said 10 receptacle, for moving said receptacle from beneath said chute and upwardly out of said trap, and causing it to eject its contents into the generating-tank.

6. In an acetylene-gas machine, the combination with the generating-tank containing water, of a chute, a trap located at the bottom of the chute and containing an inert liquid out of contact with the water in the generating-tank, a receptacle provided with a door, and having drainage communication 20 with the trap, means for moving the receptacle from beneath said chute and raising it out of said trap, means for holding the door of the receptacle closed and means for opening said door when the receptacle is raised as 25 aforesaid, so as to cause it to eject its contents into the generating-tank.
